United States Patent

Des. 240,788
Patented Aug. 3, 1976

240,788

PLATE OR SIMILAR ARTICLE

Seiichi Makita, Nagoya, Japan, assignor to Noritake Co.,
Limited (Nippon Toki Kabushiki Kaisha), Nagoya,
Japan

Filed Apr. 25, 1975, Ser. No. 572,474

Claims priority, application Japan Nov. 6, 1974

Term of patent 7 years

Int. Cl. D7—01

U.S. Cl. D7—35

FIG. 1 is a plan view of a plate or similar article embodying my new design; and

FIG. 2 is a side elevational view thereof partly in section.

The surface decoration has been omitted from the interior of the plate in FIG. 2 for convenience of illustration.

I claim:

The ornamental design for a plate or similar article, as shown and described.
